UNITED STATES PATENT OFFICE.

CHARLES W. CROWELL, OF SALISBURY, NORTH CAROLINA.

STEAM-BOILER AND APPLIANCES.

1,270,017.

Specification of Letters Patent. Patented June 18, 1918.

Application filed October 31, 1914. Serial No. 869,647.

To all whom it may concern:

Be it known that I, CHARLES W. CROWELL, of Salisbury, in the county of Rowan, and in the State of North Carolina, have invented a certain new and useful Improvement in Steam-Boilers and Appliances, and do hereby declare that the following is a full, clear, and exact description thereof.

My invention relates to steam boilers, and while I have had in view particularly the application thereof to horizontal, or approximately horizontal boilers for use on railway locomotives, ships and big stationary plants, it is to be understood I do not restrict my invention in such of its characteristics as do not require a particular type of boiler, to application of boilers of the kind named. Inasmuch as this application discloses subject matter common with that of an application filed by me April 5, 1911, Serial No. 619,051, the present application is a continuation of that application in respect of the subject matter common to both.

The object sought to be achieved by my present invention is the provision, in the best and most complete embodiment of the invention, of a boiler, suited for high pressure and quick steaming, of small initial building cost and repair, which will be of long life, equalize expansion and contraction, economical in the consumption of fuel and utilize to the utmost the unconsumed gases, or products of combustion which leave the fire box by utilizing them before they can escape into the atmosphere; and in which any desired kind of fuel may be burned.

In the accompanying drawings which are for the purpose of illustration only—

Figure 1 is a longitudinal section of one embodiment of my invention, as embodied in a locomotive boiler;

Fig. 2 is a vertical transverse section on two planes, one passing through the fire box and the other through the fire chamber;

Fig. 3 is a rear elevation of the boiler;

Fig. 4 is a detail view in side elevation showing one method of constructing the adjoining portions of the fire box and the fire chamber;

Fig. 5 is a longitudinal section of a different construction embodying my invention showing another manner of its use;

Fig. 6 is a transverse vertical section thereof on the line 6—6 of Fig. 5;

Fig. 7 is a detail view on a larger scale

showing the location of the man hole construction I prefer.

In the embodiment of my invention illustrated in the drawings, the boiler shell 10, 60 is, generally described, of cylindrical form, but of larger diameter at its rear end where it is situated in the form of my invention shown in Fig. 1, a fire box and a fire chamber one in advance of the other, the rear one 65 being the fire box, and which is designated 11 and contains the grate 12 and the front one, which for convenience and designation, I shall term the fire chamber, and which is designated 13, these being also preferably 70 cylindrical in form, and the shell 14 thereof being preferably a single sheet, although the two may be constructed of separate sheets, or shells placed end to end or abutting against each other, between flue sheets 75 16 and 17. When made in a single sheet assistance is given the stay bolts 15 and 19 in supporting the weight of the flues, or fire tubes, which are secured to the fire box and the fire chamber and the strain from expansion and contraction is better withstood. The stay bolts 15 extend in essentially radial directions between the boiler shell 10 and the fire box shell 14.

The front end of the fire box 11 is closed 85 by a vertical flue sheet 16 and the front and the rear ends of the fire chamber 13 are closed by vertical flue sheets 17 at the rear end and 17' at the front end. A full set of fire tubes, or flues 18 connect the flue sheet 90 of the fire box and rear flue sheet of the fire chamber, said fire chamber and said sheets are also connected by stay bolts 19, and the space between said front and rear flue sheets is in communication with the interior of the 95 boiler by holes 20 in the shell 14, so that the fire tubes 18 are covered with the water in the boiler. The fire box flue sheet 16 and the fire chamber rear flue sheet 17 at the bottom portion are inwardly turned about alining 100 openings in the two flue sheets for the reception of a collar 21 that is riveted to said flanges and said flue sheets have outturned flanges riveted to the shell 14, the flange or flue sheet 16 being also riveted to a portion 105 of the mud frame, all as best shown in Fig. 7. By the flange and collar construction, a horizontal man-hole 22 is provided that gives access to the interior of the fire chamber at the bottom thereof below the grate in 110 the fire box. While I do not limit myself to any particular construction of man hole,

that constructed as just described is very desirable in that it can be removed bodily with the fire chamber and fire box and with all the flues, if so desired, through the opening provided through the back head 24 in the rear end of the boiler shell without removing the mud frame 23 or the back head 24 or interfere with the staying of either, or their connections to the boiler shell 10 and 10 it possesses the very important advantage that it expands and contracts together with the fire box forward and backward and thus avoids danger of leaks which might be expected if it entered through the shell of 15 boiler and the fire chamber. The bottom of the inner shell 14 that is coextensive with the fire box 11 is cut away to provide for the grate so that that portion of the shell 14 is arc, or crescent shape in cross section. A 20 mud frame 23 is provided between the bottom portion of the boiler shell 10 and the bottom portion of the fire box shell 14 and the boiler shell 10 to the rear of the mud frame is cut away in correspondence with 25 the cut away of the bottom portion of the shell 14 of the fire box.

The back end of the boiler extending between the outer shell 10, and the inner shell 14 is closed by a back head 24, the opening 30 in which is preferably slightly larger in diameter than the shell 14 of the fire box and fire chamber having a filling rim 25 secured between the edges of shell 14 and head 24, so that both fire box and fire chamber may, 35 when necessary, pass through such opening after removing rim 25. Of course, if it should not be necessary to remove the fire chamber the fire box 11 alone could be thus removed, this being possible by separating it 40 from the fire chamber, either by cutting the shell between them in two, if a single shell is employed, or by disconnecting them if the shell portion of each is separately made from the other. A filling ring 25, as of 45 metal, is placed between the outside of the fire box shell at the rear end and the interior of the hole through the back head 24 so as to closely fill up the slight space provided for the passage of the fire box shell 50 14 through the opening in the back head.

The portion of the fire box shell contiguous to the man hole is cut away, or a large opening 26 is provided in order to prevent mud accumulations, or deposit around the 55 man hole and also to render the structure convenient for building and repair or removing without interfering with the other construction.

Within the fire chamber 13 there is a partition 27 that rises from the bottom thereof 60 between the front flue sheet 17' and back flue sheet 17 to a desirable point, thence forward to the front flue sheet 17', constituting a supplementary combustion chamber 28 in 65 the forward lower portion of the fire cham-

ber 13. From the fire chamber 13 above said partition, a group of fire tubes 29 pass forward to a flue sheet 30 at the rear end of the smoke box 31 and from the bottom of said smoke box a group of flues 32 extends 70 rearward and communicates with the interior of the combustion chamber 28 at the bottom thereof and from the upper part of said combustion chamber a group of flues 33 extend forward to an inner or supplemental smoke chamber 34 in the smoke box 31 from which smoke chamber 34 a pipe 35 leads to the stack, while into the bottom of said smoke chamber 34 reaches a pipe, or conduit 36 for exhaust steam. The group 80 of tubes 29 is larger in number than the group of tubes 32 and the latter is larger in number than the group of tubes 33, so that as it will be seen from the arrangement shown and described, the gas and 85 products of combustion will pass from the fire box 11 through flues 18, thence through the fire chamber 13 forward through the flues 29 to the smoke box 31, thence back through the flues 32 to the combustion chamber 28 and finally forward from the latter through the flues 33 to the outlet through 90 chambers 34 and stack 35. The gradual, diminishing capacity of the tubes produces a condition equivalent to a long tapered 95 smoke chimney. Inasmuch as air, steam, oil, or other combustible, or means for promoting combustion, is introduced into the combustion chamber 28, as I hereinafter more fully point out, with which the furnace gases, or unconsumed products of combustion that reach such chamber are thoroughly mixed in the lower part of the combustion chamber 28, and as the contents of 100 said combustion chamber 28 are subjected 105 to fierce heat from the partition 27 (which is exposed to the heat from the fire box 11 and preferably is made of fire brick, or the like) they are ignited and it will be seen that the extraction of heat in a high degree is secured from the fuel used and it is applied to the water in the boiler by the 110 passage of the high temperature derived from the combustion of gaseous products in chamber 28, through the third group of fire 115 tubes 33 before the stack is finally reached. By the grouping of the flues, and extending them to the top of the flue sheet 30, and arranging parts mentioned therewith, as shown and described, I provide a return 120 tube boiler and get a large area of heating surface.

For the supply of air, steam, oil, or other combustible to the lower part of the combustion chamber 28, I pass a pipe 37 (or 125 more than one should it be desired) horizontally through the partition 27 from the fire chamber 13, which in the latter is formed into a coil 38 and extends through a hole, or flue in the fire box flue sheet 16 and the 130

rear fire chamber flue sheet 17 between the grate and the mud ring and leads to some convenient point outside the boiler where any desirable means may be provided for regulating the air or other agent passing therethrough. The air, or other agent is heated to a very high temperature in the coil 37 preliminary to its entering the combustion chamber 28. The partition wall 27, 5 and the pipes 37 are exposed to the heat from the fire box 11, and give additional heat to the gases as they arrive in the combustion chamber 28, and thus the air, or other fluid agent before its delivery to the 10 combustion chamber 28 is highly heated so that it most efficiently promotes the combustion of gases entering the combustion chamber 28 through the flues 32.

The double shell construction with the 20 bottom portions of both shells cut away to provide the grate opening, besides advantages I have before pointed out is an advantage in that it permits of easy access to the fire box, or fire chamber in that the man hole 25 tube can be located, as I have shown, where it gives ready access to the fire chamber and expands and contracts equally with its connections.

As shown in Fig. 4, the rear fire box 11, 30 and the fire chamber 13 have independent shells and they are abutted together, or placed endwise and joined by numerous plates 39 riveted to adjacent portions of the respective shells.

35 In the form of my invention illustrated in Figs. 5 and 6, the fire chamber 40 is located farther forward than in the construction shown in Fig. 1 so that the fire tubes corresponding to the fire tubes 18, shown in Fig. 40 1, are, of course, of greater length and a partition 41 is provided which may be of sheet metal, or fire brick corresponding with the partition 27, when the structure shown in Fig. 1 is employed to provide the supplementary combustion chamber in the lower forward side of the fire chamber. A baffle 42 consisting of two horizontally projecting plates, one of which is adjustable, is extended from the front flue sheet 17' rearward in 45 the case of both the structures illustrated in Figs. 1 and 2 in order to direct the currents issuing from the lowermost group, or tubes 32 in the combustion chamber 28. The structure shown in Figs. 5 and 6 is similar to what appears in my aforesaid Patent No. 55 1,115,787, and may be used in connection with any kind of fire box.

My fire chamber and combustion chamber and return flue arrangement is not dependent upon the particular type of fire box shown in Fig. 1, as will be noticed in the drawings Fig. 5, as well as the drawings in Fig. 1 of Patent No. 1,115,787.

In designing and building the described construction, the flue sheet 30 may be made as

large as desired to carry the number of flues wanted. The outer shell 10 extending about the inner shell 14 may be made as large as possible for locomotives, and tapered from near the front portion of the inner shell forward to a point near the flue sheet 30. The inner shell 14 may be made the same size as the flue sheet 30, but in order to get more grate and heating area, it can be made larger than the flue sheet 30 by placing the 70 top the same height as the top of flue sheet 30, and reducing the width of the mud frame 23. By so doing it enables me to get more than the required grate area per heating flue, the grate area 12 is figured against 75 the number of flues in series 29 only. The back head of the boiler shell is placed in the edges of said inner and outer shells at the rear end, said back head and the mud frame 23 being stayed to shell 10, as shown in Figs. 1 and 2, and are permanently located being finished up before the inner shell 14 is inserted, said inner shell may be built on the outside with or without all parts secured therein, and inserted through the opening in 80 the back head 24 and secured to the mud frame with filling rim 25 inserted between the opening in the back head and said inner shell and secured therein, after which stays 85 15 can be secured between said inner and outer shells. It is preferred though in Fig. 1 that the front head 43 and rear head 44 forming the rear water wall 45 in the rear end of the inner shell 14 and the flue sheets 16 and 17 with flues 20 and man hole 22, 90 and the flue sheet 17' all be installed in said inner shell before it is inserted into the boiler shell.

In repairing my described construction either head 43 or 44 may be renewed or both 105 and all rivets held from the outside by removing the filling rim 25.

To renew the fire box 11 if shell 14 is in one sheet, cut shell in two between flue sheets 16 and 17, remove flues 18, remove rivets 110 from man hole 22 which are secured to flue sheet 16, remove stay bolts 19, and the rivets from the mud frame 23, remove stays 15 and the filling rim 25, and the fire box 11 will pass out rearward without removing 115 the mud frame 23 or the back head 24 or the staying of either.

The fire box may also be removed in the same manner, and leave the flue sheet 16 and the flues 18 intact.

120 The flue sheet 16 may be renewed alone, or include the flue sheet 17, flues 18, stay bolts 19, and man hole 22.

The man hole tube may be removed rearward alone by cutting rivets loose from flue 125 sheets 16 and 17. The shell 14 around fire box 11 and fire chamber 13 may be made in one piece, but for convenience in repairing it may be made in two sections, and butted together between the flue sheets 16 and 17, 130

and secured together with butt straps 39 shown in Fig. 4.

By cutting the flues 29, 32, and 33 loose from the flue sheet 30 and removing stays 5 15 and cutting rivets loose from the mud frame 23 and removing filling rim 25, all of the flues, the combustion chamber 28, the fire chamber 13, the fire box 11 and the man hole tube 22 may be removed in a body 10 through the opening in the back head 24.

The man hole tube 22, has a cover 46 to be removed for entering fire chamber 13.

Having thus described my invention what I claim is—

15 1. A steam boiler having a fire box, a fire chamber and a smoke box arranged in advance of each other, all being substantially circular in cross section, a group of flues extending from said fire box to said fire chamber, and a second group of flues extending from said fire chamber to said smoke box forming a forward passage, a third group of flues forming a rearward passage from said smoke box to a combustion chamber within said fire chamber, and a fourth group of flues forming a forward passage to an inclosed member in said smoke box, having an outlet thence through a stack.

20 2. A steam boiler having inner and outer shells spaced apart, both being substantially cylindrical with portions removed at their bottoms forming an opening for grates, a grate situated therein, said shells having a mud frame extending around the edges of said opening and between said shells and secured thereto; a portion of said inner shell extending forward from its connection at the front portion of the mud frame a distance from said grate opening, a flue sheet 25 in its forward end and heating flues extending forward therefrom in three groups, upper, lower, and intermediate, a combustion chamber being formed between said shells and said flue sheet in advance of said grate opening, and means for directing the flames and gases forward through said upper series of flues; thence through said lower series into said combustion chamber, and thence forward through the intermediate series to the outlet.

25 3. A steam boiler having inner and outer shells spaced apart, both being substantially cylindrical with portions removed at their bottoms forming an opening for grates, a grate situated therein, said shells having a mud frame extending around the edges of said opening and between said shells and secured thereto, said inner shell being extended forward beyond the mud frame a 30 distance and having a flue sheet in the front portion thereof, a flue sheet in the front portion of said outer shell, heating flues connecting said flue sheets, said inner and outer shells being formed and arranged in position so as to allow the tops of said flue

sheets to be placed substantially on a horizontal line with each other and said heating flues extending to the tops thereof.

4. A steam boiler having inner and outer shells spaced apart, both being substantially cylindrical with portions removed at their bottoms forming an opening for grates, a grate situated therein, said shells having a mud frame extending around the edges of said openings and between said shells and secured thereto, a portion of said inner shell extending forward from its connection at the front portion of the mud frame a distance from said grate opening, a flue sheet in its forward end, and heating flues extending forward therefrom, said inner shell being removable through the opening in the back head 24 of the boiler, by cutting rivets 75 from its connection and from said mud frame connection.

5. A steam boiler having inner and outer shells spaced apart, both being substantially cylindrical with portions removed at their bottoms forming an opening for grates, a grate situated therein, said shells having a mud frame extending around the edges of said opening and between said shells and secured thereto, a fire chamber in said inner shell extending forward from said mud frame, a fire box being above said grates and two flue sheets forming a water wall between said fire chamber and fire box having heating flues secured therein, a man hole formed in said flue sheets through said water space below said grates and above said mud frame for gaining admission into the fire chamber.

6. A steam boiler comprising inner and outer shells spaced apart, a back head secured between the rear ends thereof, having an opening therein for the reception of an open bottom fire box, the opening in said back head being greater in size than said fire box, a member being fitted between the edges of said back head opening and said fire box, said member being removable, so that the fire box may be easily inserted, or withdrawn through said opening.

7. A steam boiler having a fire box and a fire chamber consisting of a substantially cylindrical shell, three flue sheets, front, rear, and intermediate spaced apart and secured therein, two heads secured in the rear end of said shell forming a rear water wall, a water wall being formed between said rear and intermediate flue sheets which separates said fire box and fire chamber, heating flues extending therethrough, said front flue sheet being secured in the front end of said shell and heating flues extending therefrom, holes 115 being provided in said shell for the circulation of water between the rear and intermediate flue sheets, a grate opening being provided in the bottom of shell extending between said rear flue sheet and rear water 120 125 130

- wall, said fire box and chamber being removable through the boiler head rearward.
8. A steam boiler having a fire box and a fire chamber consisting of a substantially cylindrical shell having three flue sheets front, rear, and intermediate, spaced apart therein, the fire chamber being in front of the fire box, heating flues extending forward from said front flue sheet, other heating flues extending from said rear flue sheet to said intermediate flue sheet, a water wall consisting of two heads spaced apart and secured in the rear end of said shell, a grate opening being provided between said water wall and said rear flue sheet, a grate secured therein, said fire box and fire chamber being removable through the rear end of the boiler.
9. The combination in a steam boiler having a fire box and a fire chamber consisting of a substantially cylindrical shell having three flue sheets, front, rear, and intermediate spaced apart therein, the fire chamber being in front of the fire box, heating flues extending forward from said front flue sheet, other heating flues extending from said rear flue sheet to said intermediate flue sheet, a water wall consisting of two heads spaced apart and secured in the rear end of said shell, a grate opening being provided between said water wall and said rear flue sheet, a grate secured therein, a man hole tube extending from rear flue sheet to said intermediate flue sheet for entrance to said fire chamber, a portion of said shell extending between said rear and intermediate flue sheets being removed sufficient to prevent mud from settling around said man hole tube, and to make it easy in building and repairing same, other openings being made in said shell between said rear and intermediate flue sheets to allow water to circulate through the top thereof, and openings being formed in said shell between said rear heads for the circulation of water there between said construction being removable through the rear end of boiler.
10. A steam boiler comprising an inner and an outer shell, said inner shell having an opening in a portion of its bottom, three flue sheets spaced apart therein forming a fire chamber in advance of the fire box, a combustion chamber formed within said fire chamber, flues extending between said fire chamber and fire box, a pipe leading from the outside of boiler through the fire chamber into said combustion chamber for heating and conveying air or other fluid agent into said combustion chamber.
11. A steam boiler comprising an inner and an outer shell, the inner shell having a grate opening in a portion of its bottom, a fire box and a fire chamber formed therein, flues extending between said fire box and fire chamber, other flues leading from said

fire chamber, a combustion chamber formed in a portion of said fire chamber and means for heating and delivering air or other fluid agent into said combustion chamber from the outside of the boiler.

12. A steam boiler comprising an inner and an outer shell both being substantially circular in cross section, said inner shell having three flue sheets spaced apart therein, front, rear, and intermediate forming a fire chamber and a fire box therein, said inner and outer shells having a grate opening in their bottoms extending rearward from said rear flue sheet, the fire chamber being formed between said intermediate and front flue sheets and having a combustion chamber formed therein for igniting and returning the flames, means for admitting air or other fluid agent into said combustion chamber from a feeding point through said fire chamber.

13. A boiler having a fire chamber, a combustion chamber and means for discharging flames, gases, or other combustible matter from the fire chamber through another portion of the boiler, and then into the combustion chamber to be consumed, and discharge through another portion of the boiler to the outlet, said fire chamber and combustion chamber being separated by a partition wall, said partition wall being exposed to the fierce heat of the fire chamber for increasing the temperature, and igniting gases in said combustion chamber.

14. A boiler having inner and outer cylindrical shells, an open bottom fire box formed in the rear portion of said shells, flue sheets spaced apart in the forward end of said inner shell and forming a fire chamber, heating flues extending forward from the front sheet of said fire chamber, heating flues connected to the flue sheets between said fire box and said fire chamber, a partition dividing the fire chamber in two parts, the lower front part forming a combustion chamber, said partition being arranged for directing the flames from the fire box through the upper part of said fire chamber, and for receiving them in the lower part of said combustion chamber where combustion takes place and directing the heat upward and forward through said combustion chamber.

15. In a boiler, a fire box and a fire chamber being separated by two flue sheets, said fire box having an opening with grates in said opening, a man hole for entering said fire chamber being provided through said flue sheets below said grates.

16. A boiler having a fire box with a flue sheet in its forward end, a fire chamber forward of said flue sheet, heating flues communicating with said fire box and the rear end of said fire chamber, other heating flues extending forward from said fire chamber,

- a partition arranged in said fire chamber forming a combustion chamber, means for passing the flames and gases from the fire box over said partition into the flues, and returning them into the lower part of said combustion chamber, and one or more pipes leading into said combustion chamber for the purpose of discharging hot air or other combustible matter into said combustion chamber to ignite the unconsumed combustible matter received in said chamber from the flues.
17. A boiler having a smoke box and a fire box, a chamber circular in cross sections having front and rear flue sheets, heating flues communicating with said rear flue sheet and the fire box, other heating flues communicating with said front flue sheet and the smoke box, and which are divided into upper, lower, and intermediate series, a partition dividing said circular chamber into two parts and forming a combustion chamber of the lower front part, said partition separating the lower and intermediate series of flues from the upper series, also separating the lower and intermediate series of flues from the flues in the rear flue sheet, the flues from said rear flue sheet all discharging in one portion of said circular chamber and passing out through the upper series into said smoke box and returning through the lower series into said combustion chamber where the unconsumed gases are mixed with hot air or other combustible matter admitted into said chamber, and a pipe, or pipes from the outside of boiler, entering the combustion chamber to ignite the gases and pass the heat forward again through the intermediate series of flues to the outlet.
18. A steam boiler having a fire box, a fire chamber forward of said fire box, a combustion chamber within said fire chamber, a smoke box forward of said fire chamber, a group of heating flues extending between said fire box and the rear end of said fire chamber, three groups of heating flues, upper, lower and intermediate, extending between the front head of said fire chamber and said combustion chamber to the flue sheet of said smoke box, and means for returning the flames and gases from said fire chamber through said upper series of flues into said smoke box, thence through said lower series of flues into said combustion chamber, thence through the intermediate series of flues to an inclosed member in said smoke box, thence through a conduit to the outlet, the capacity of the groups of flues in the successive series being graduated.
19. The combination in a steam boiler having a fire box, a smoke box, a fire chamber and heating flues, said fire box having a flue sheet in its forward end, said fire chamber having a flue sheet in each end, a partition in said fire chamber dividing it in two parts, the lower part forming a combustion chamber, and said heating flues extending from the flue sheet of the fire box to the rear flue sheet of said fire chamber into which they discharge over and against the rear side of said combustion chamber, other of said heating flues extending from the front flue sheet of said fire chamber to the flue sheet of the smoke box and divided into three series, upper, lower, and intermediate, and means for returning the flames and gases from said fire chamber and upper series of flues, through said smoke box and lower series of flues into said combustion chamber, thence through the intermediate series to the outlet.
20. A steam boiler having an inner and an outer shell, said inner shell comprising three distinct chambers therein, a fire box, a fire chamber, and a combustion chamber and heating flues communicating with each chamber.
21. A steam boiler having an inner and an outer cylindrical shell spaced apart, said inner shell containing three chambers, the rear one of which has an opening in the bottom for the reception of a grate, said outer shell being cut away under the grate, a fire chamber forward of said rear chamber having another chamber formed therein, and heating flues communicating with all three chambers.
22. A boiler having a fire box, a fire chamber forward of said fire box, means for the discharge of products of combustion from said fire box to said fire chamber, a combustion chamber, and one or more pipes for delivering air or other combustible matter into the combustion chamber that leads from outside the boiler into the fire chamber where it is subjected to heat therein, and thence passes into said combustion chamber.
23. A boiler having a fire box, a fire chamber forward of said fire box means for the discharge of products of combustion from said fire box to said fire chamber, a combustion chamber, and one or more pipes for delivering air or other combustible matter into the combustion chamber that leads from outside the boiler into the fire chamber where it is subjected to heat therein, and thence passes to said combustion chamber, said fire chamber being composed of a shell and two flue sheets, and the combustion chamber being formed therein by a partition that divides off a portion of the interior of said shell.
24. A steam boiler having a smoke box, a fire chamber, a combustion chamber within said fire chamber, a group of flues extending from said fire chamber to said smoke box forming a forward passage, a second group of flues extending from said smoke box to said combustion chamber forming a 130

- rearward passage, a third group of flues extending from said combustion chamber forming a forward passage to the outlet through said smoke box.
- 5 25. The combination in a steam boiler having a fire box, a flue sheet in its forward end, a fire chamber in advance of said fire box, a flue sheet in its rear end, both being substantially circular in cross section, the fire box having an opening for the reception of a grate, the shells of said fire box and said fire chamber extending beyond said flue sheets, and being abutted together about midway the distance between said flue sheets, and butt straps securing the abutted ends together so that said fire box may be removed rearward through the rear end of the boiler without moving said fire chamber by cutting butt straps loose from the 10 tension of the shell of said fire box, openings being provided in the abutted ends of said shell for the circulation of water between said flue sheets, heating flues, a man hole tube and stay bolts being secured in 15 said flue sheets, and a portion of the abutted ends of said shells being removed from the bottom to prevent mud from settling around said man hole tube, also to make it convenient for building and repairing said man hole connection.
- 20 30 26. A steam boiler comprising inner and outer shells spaced apart, a back head secured in the rear ends thereof, having an opening for the reception of an open bottom fire box, the opening in said back head being greater in size than said fire box, a member being fitted between the edges of said back head opening and said fire box, and being removable so that the fire box may be easily 35 inserted, or withdrawn through said opening.
- 35 40 27. The combination in a steam boiler comprising an inner and an outer shell both being substantially cylindrical and having an opening in a portion of their bottoms, a mud frame fitted between said shell bounding the edges of said opening, a flue sheet, heating flues, and a combustion chamber, said inner shell extending forward from 45 said mud frame and said opening, said flue sheet secured in its front end, heating flues extending forward therefrom being divided into upper, lower, and intermediate series, a partition wall resting against said flue sheet and against said inner shell forming 50 said combustion chamber and dividing the upper series of flues from the lower and intermediate series, and means for directing the flames and gases forward through the 55
- upper series of flues and returning them into 60 said combustion chamber through the lower series of flues thence forward through the intermediate series to a point of discharge.
28. A steam boiler comprising an inner and an outer shell, the inner shell having an 65 opening in its bottom, a fire chamber in its forward end, a combustion chamber formed within said fire chamber, flues connecting said fire chamber from its rear end and flues communicating with the fire chamber and 70 the combustion chamber, and means including flues connecting the combustion chamber with the stack.
29. A steam boiler having a fire box, a combustion chamber and heating flues, said 75 heating flues being divided into upper, lower and intermediate series, said combustion chamber being separated from said fire box by a partition wall, and arranged in position so as to allow the flames and gases from 80 said fire box to pass forward above said combustion chamber, through said upper series of flues, thence through said lower series of flues into said combustion chamber, thence forward through said intermediate 85 series of flues to a point of discharge.
30. A boiler having a fire box, a fire chamber forward of said fire box having a partition dividing it into two compartments, one of which is a combustion chamber, flues 90 connecting the fire box and the fire chamber on one side of said partition, flues leading from said fire chamber and communicating with the combustion chamber on the other side of said partition, and flues leading 95 from said combustion chamber to the outlet.
31. In a boiler, a fire box, a fire chamber in advance of said fire box having a combustion chamber formed therein by a partition at its forward end made of refractory material, said partition being exposed to flames and gases from its rear side for increasing the temperature in said combustion chamber, and means for directing the flames and gases over said combustion 100 chamber through a portion of the boiler, and returning them through another portion of the boiler into said combustion chamber for the gases to be ignited and discharged through another portion of the boiler to the 105 outlet.
- 110 In testimony that I claim the foregoing I have hereunto set my hand.
- CHARLES W. CROWELL.
- Witnesses:
- M. L. GANTT,
WILLIE LEE.
